UNITED STATES PATENT OFFICE.

CHARLES E. MITCHEM, OF CHICAGO, ILLINOIS.

REMNANT-TAG.

1,079,425.

Specification of Letters Patent.

Patented Nov. 25, 1913.

Application filed May 17, 1912. Serial No. 697,991.

To all whom it may concern:

Be it known that I, CHARLES E. MITCHEM, a citizen of the United States, residing at Chicago, in the county of Cook and State 5 of Illinois, have invented a new and useful Remnant-Tag, of which the following is a specification.

The present invention relates to improvements in remnant tags, the primary object 10 of the same being the provision of a flexible tag adapted to be used in connection with the resilient band clip as shown in applicant's former Patent No. 790,449, dated May 23, 1905, the present structure over- 15 coming the disadvantages of the tag as shown in said patent and providing a means in addition to the spur carried by the clip for holding the tag upon the remnant and against movement therefrom that will permit 20 of the passage of one terminal of the band through the body of the tag and thus insure absolutely the proper positioning of the tag with relation to the band and consequently prevent the loss therefrom while 25 in remnant embracing position.

With the foregoing and other objects in view which will appear as the description proceeds, the invention resides in the combination and arrangement of parts and in the 30 details of construction hereinafter described and claimed, it being understood that changes in the precise embodiment of the invention herein disclosed can be made within the scope of what is claimed without 35 departing from the spirit of the invention.

In the drawings—Figure 1 is an end elevation of the remnant tag and supporting band with the portion adjacent the center of the band and tag in section. Fig. 2 is a 40 side elevation of the remnant tag taken from the left as viewed in Fig. 1. Fig. 3 is a plan view taken from the left as viewed in Fig. 2. Fig. 4 is a section taken on line 4—4 of Fig. 3. Fig. 5 is a plan view of the tag *per se*. Fig. 6 is a perspective view illustrating the attachment of the present remnant tag to a remnant. Fig. 7 illustrates a modification of the present device.

Referring to the drawings, the numeral 1 45 designates an arched resilient band or clip having the outwardly bent terminal 2 to provide a means whereby the said clip may be readily inserted upon a rolled remnant R to embrace the same and thus retain the tag 4 in remnant embracing position. The 50 clip 1 is formed similar to the clip shown in

the aforementioned patent and is provided with a spur 3 which is disposed to engage the outer surface of the tag 4 but not penetrate the same.

It has been found in practice that the spur 3 does not under certain conditions properly retain the tag 4 against longitudinal movement, or movement that would tend to remove the tag from between the clip 1 and the remnant R, and that therefore in order to insure the proper positioning or retention of the tag 4 in remnant embracing position, the slot or opening 5 is formed through the body of the tag 4 at one terminal thereof, as clearly shown, and is provided with the straight edge 6 and the curved edge 7 so as to permit of the easy introduction of one of the terminals 2 of the clip 1 therethrough as clearly illustrated 60 in Figs. 1, 2 and 4.

In putting the present remnant tag in use, the tag 4 having placed thereon the price and size of the remnant, the tag is positioned against the exterior surface of one 80 side of the remnant R, and the clip 1 taken in the other hand of the operator so that both terminals fit astride the remnant, the terminal 2 being inserted through the slot 5, the operator pushing the clip home 85 against the body of the remnant R until the spur 3 has been pressed against the outer surface of the tag 4. Thus the tag is held in permanent embracing position and by reason of the spur 3 and the slot 5, the said 90 tag 4 is retained against accidental displacement.

If so desired as shown in Fig. 7, the spur 3 may be dispensed with, the slot 5 being the main essential in properly retaining the tag 4 in remnant embracing position.

By this means, it will be seen that the tag 4 and clip 1 under ordinary conditions are separate, the tag 4 being formed in a flat oval blank, as shown in Fig. 5, and only 100 curved to embrace a remnant R after the same has been written upon, to indicate the size and price of the remnant, by means of the positioning of the clip as heretofore described with relation thereto and the remnant. By employing a single slot 5 at a point near one end of the blank or tag 4, the clip is readily placed in proper position, both as to the tag 4 and the cylindrical or rolled remnant, without tearing out the material 110 below the slot 5, during such positioning of the parts upon the remnant. This fea-

ture is of the utmost importance, in that it provides a means for readily placing the tag upon the remnant and retaining the same against accidental displacement.

5 What is claimed is:

In a device of the class described, a tag provided at one end only with an opening; an arched, resilient clip extended transversely of the outer face of the tag, both ends 10 of the clip being extended beyond the ends

of the tag, and one end only of the clip being threaded through the opening, and extended beneath the corresponding end of the tag.

In testimony that I claim the foregoing as my own, I have hereto affixed my signature in the presence of two witnesses.

CHARLES E. MITCHEM.
